UNITED STATES PATENT OFFICE.

FRANK C. DE REAMER, OF BRIDGEPORT, CONNECTICUT, ASSIGNOR TO GENERAL ELECTRIC COMPANY, A CORPORATION OF NEW YORK.

ELECTRIC SNAP SWITCH.

Application filed March 4, 1924. Serial No. 696,889.

To all whom it may concern:

Be it known that I, FRANK C. DE REAMER, a citizen of the United States, residing at Bridgeport, county of Fairfield, State of Connecticut, have invented certain new and useful Improvements in Electric Snap Switches, of which the following is a specification.

The present invention relates to electric snap switches and has for its object to improve their construction to the end that they shall be small, simple in construction, cheap to manufacture and capable of withstanding hard usage.

15 One application of my invention is to vacuum cleaners where the switch itself is located within the handle of the cleaner and the actuator outside and is arranged to control the circuit of the operating motor.

20 For a consideration of what I believe to be novel and my invention, attention is directed to the accompanying description and the claims appended thereto.

In the accompanying drawing which illustrates one of the embodiments of my invention, Fig. 1 is a view in side elevation of a switch; Fig. 2 is an end view thereof; Fig. 3 is a perspective view of the frame; Figs. 4 and 5 are respectively a side and end view of the insulating body which supports the fixed contacts; and Fig. 6 is a side view showing how the insulating body is protected from the hammer blows of the switch lever.

35 In order that the construction of the switch may be readily understood the drawing is made on an enlarged scale, being approximately twice actual size.

It is of special importance in a switch of this character that it be small, not only in length, but also in breadth and thickness and of such character that it can be easily mounted after wiring in the handle of a vacuum cleaner or in the tube connecting the handle with the cleaner body.

40 6 indicates a U-shaped metallic supporting frame member made by dies from sheet steel and which is provided with a bottom portion and three side wall portions or steps of different heights with shoulders between. The highest portion 7 forms a stop to limit the rearward movement of the inverted U-shaped lever 8 which carries the bridging contact member 9 of the switch. Since the 45 portion 7 is U-shaped with the open end at

the top and the contact carrying lever 8 is also U-shaped with the open end at the bottom and straddling the frame, it follows that the side edges of both legs of the frame will act as a stop when the lever is moved to the right-hand or open circuit position as shown especially in Fig. 2 and thus prevents twisting. The intermediate portion 10 of the frame is cut away at an angle on both sides as indicated at 11 to form a stop for the contact carrying lever 8 when the contact is in the closed circuit position. These inclined or cut away parts are arranged to engage both legs of the switch lever and in this manner prevent twisting of the lever and the contact. The stop also prevents the contact or some movable part of the lever from delivering hammer blows on the insulating block which carries the stationary contacts. This is clearly shown in Fig. 6. 70

At or about the shoulders or junctions between the inclined surfaces 11 of the intermediate portion of the frame and the vertical walls of 12 the high part 7 of the frame, the metal is pressed outwardly by a die 80 operation to form two pivots 13 for the lever, one on each side. Since these pivots are formed integral with the frame I thereby avoid the use of additional small parts and therefore the cost of manufacture is reduced as well as the cost of assembly. The pivots extend only a short distance outwardly from the frame, which arrangement permits the legs of the lever 8 to be mounted thereon by merely springing them outwardly by a small amount in the assembly operation.

14 indicates the low portion of the frame and shoulders 15 are provided between it and the intermediate portion. The low portion of the frame is also U-shaped in cross section and seated therein is a block of insulation 16, the bottom of which snugly fits the side walls of the frame. The end of the block firmly engages the shoulders 180 15 between the low and intermediate parts of the frame, the thickness of the block at this point being slightly greater than the distance between the outer surfaces of the frame. The block is held in position by a single countersunk screw 17 inserted from the upper side. As a result of the construction described the block is firmly held against lateral or twisting movement by the side walls of the frame and against longi- 105 110

tudinal movement by the shoulders and the screw, the latter also holding the block from rising from its seat.

In the block are anchored two hollow rivets 18, one on each side. Each rivet unites a stationary spring contact 19 with a binding post 20, each of the latter having a screw to hold a circuit wire or conductor. Each stationary contact extends toward the moving switch lever and its bridging contact 9 so that when the switch is closed the stationary contacts and the lever occupy positions approximately at right angles to each other. It is to be especially noted that no portion of the stationary contacts, the binding posts or their screws extend outside of the vertical left-hand end of the block. As a result of this the overall length of the switch is reduced to a minimum and the insulation of the leads or conductors and the switch parts from their containers, whether it be a tube or other support, is simplified.

Each time the switch is closed a certain amount of strain is exerted on the fixed contacts 19 and through them on the rivets 18 due to the fact that there is friction between the relatively movable contacts. In order to relieve the rivets of some of this strain and also to prevent the contacts 19 from turning or twisting the sides of the block are countersunk at 21 as best shown in Figs. 4 and 5. A portion of the wall of each countersink is so shaped as to engage the curved lower edge 22 of a contact and thereby support it, especially during the circuit closing movement of the switch.

The moving parts of the switch will now be described. In brief, it may be stated that they comprise a member which carries a bridging contact and a toggle mechanism for actuating the member so arranged that the center hinge or pivot and the spring are caused to move across the dead center to snap the bridging contact to both its open and closed positions. In the bottom wall of the frame is a slot 23 and located therein is a handle or trigger 24 which is mounted on a horizontal pivot 25, the latter extending through both walls of the frame and having a head on one end and deformed or enlarged at the other end to prevent accidental withdrawal. Inside the frame the trigger is enlarged to form a head and on opposite sides thereof are shoulders 26 which limit its movements by engaging the bottom wall of the frame at the respective ends of the trigger movements. In the upper end of the trigger is a small fork 27, the members of which engage the enlarged lower end of the rectangular rod 28 to form a hinged connection. The upper end of the rod extends through a hole or guide in a lateral ear 29 formed integral with the cross member which connects the legs of the U-shaped

lever. Surrounding the rod and engaging the ear at its upper end and a washer at the other is a coiled compression spring 30 which when the trigger is moved a certain distance, i. e., sufficient to cause the hinge 70 joint to pass the dead center, snaps the contact 9 to its open or closed position as the case may be.

As previously stated the lever 8 is in the form of an inverted U and is made of sheet 75 metal by suitable die operations. The lower ends of the legs straddle the frame and move on pivots 13, while the upper and connecting end or member is somewhat 80 narrower than the space between the side walls of the frame, the upper and lower end portions of each leg being connected by inclined portions 31 as best shown in Fig. 2, and it is these portions which strike the vertical edges of the frame part 7 when 85 the switch opens and which strike the inclined edges 11 of the intermediate part when the switch closes.

By arranging the parts in the manner described the distance between the outside surfaces of the contact 9 may be made slightly less than the thickness of the block of insulation with the net result that the switch as a whole is very thin and hence occupies only a narrow space in its holder or container.

As the metallic lever 8 carries the U-shaped contact 9 it is necessary to insulate these parts one from the other. This is done by providing a U-shaped piece of insulation 32 between the two. In order to unite the lever, contact and insulation a single hollow eyelet or rivet 33 is employed which extends through the bridge piece of the lever and is insulated from the contact by a small sleeve and washer. It is to permit of properly insulating the contact that the outwardly extending ear 29 is provided.

Owing to the fact that the contact 9 has three broad flat surfaces, i. e., a top and two sides, and is forced down over the lever, the insulation between it and the lever has no opportunity to twist or turn and hence a single rivet is sufficient to hold it in place.

The frame of the switch is secured in the handle or tube of a vacuum cleaner indicated by dotted lines in Fig. 1 by a pair of small screws which enter the threaded openings 34, and the trigger extends through a slot in the wall of the handle or tube so as to be accessible from the outside. In practice, the circuit wires or conductors are passed through the handle or tube and the ends connected to the binding posts after which the switch is pushed into the tube or handle to the proper position and then held by screws.

What I claim as new and desire to secure by Letters Patent of the United States, is,

1. In an electric switch, the combination of a frame which is U-shaped in cross section

and has high, low and intermediate side wall portions with shoulders between them, a body of insulation seated on the bottom of the frame between the low side walls and engaging a shoulder, fixed contacts on the body which extend toward said high portion, a contact arranged to bridge the fixed contacts, a lever which carries the bridging contact, and toggle means for actuating the lever, the movements of the lever and contact being limited in one direction by the high portion of the frame and in the opposite direction by the intermediate portion thereof.

2. In an electric switch, the combination of a frame which is U-shaped in cross section and has high, low and intermediate side wall portions, a body of insulation carried by the low portion, fixed contacts on the sides thereof, a pair of outwardly extending pivots carried by the intermediate portion, an inverted U-shaped lever which straddles the intermediate portion and moves on the pivots, the movements of the lever in one direction being arrested by the upper edges of the intermediate portion, and in the opposite direction by the edges of the high portion of the frame, an insulated contact carried by the lever and arranged to bridge the fixed contacts, and a toggle which comprises a trigger pivoted to the frame and a member associated with the trigger and lever for moving the latter and its contact with a snap action to both of its positions.

3. In an electric switch, the combination of a frame which is U-shaped in cross section and has high, low and intermediate side wall portions with shoulders between them, a body of insulation which is seated on the bottom of the low portion of the frame, is held by the walls thereof from turning and firmly engages one of the shoulders, means for fastening the body to the bottom of the frame, fixed contacts carried by the sides of the body and extending toward the high portion of the frame, pivots carried by the intermediate portion of the frame and extending outwardly therefrom, an inverted U-shaped lever which straddles the intermediate portion of the frame and is mounted on the pivots, said lever being arrested at the end of one of its movements by the edges of the intermediate portion of the frame, and at the end of its other movement by the shoulder between the intermediate and high portions of the frame, a bridging contact carried by the lever and insulated therefrom, and toggle members for actuating the lever and its contact with a snap action.

4. In an electric switch, the combination of a frame which is U-shaped in cross-section, a body of insulation mounted thereon at one end and having recesses in the sides, fixed contacts located in said recesses, said contacts being anchored adjacent one end and having free ends extending from the

recesses, the walls of which assist in supporting the fixed contacts adjacent their free ends by engaging a portion of the edges thereof, an inverted U-shaped lever which straddles the frame, pivots on the frame for the lever, a contact carried by the lever and insulated therefrom which is adapted to bridge the fixed contacts, and toggle means for moving the bridging contacts by snap action into and out of engagement with the fixed contacts.

5. In an electric switch, the combination of a frame, a pair of fixed contacts mounted on the frame and insulated therefrom, an inverted U-shaped lever which straddles the frame and is pivotally supported thereby at its open end, said lever having an ear which extends laterally from the connecting member thereof and has a guide opening, an insulated contact mounted on the member and arranged to bridge the fixed contacts, a rod which extends through the guide opening in the ear, a trigger which is hinged to the rod, a spring, said rod, trigger and spring forming a toggle means for moving the lever to open and close the circuit at the contacts by a snap action, and means formed in the lever and on the frame which cooperate to provide stops for limiting the movement of the lever between said open and closed circuit positions.

6. In an electric switch, the combination of a metallic frame, a U-shaped metallic lever pivotally supported at its open ends on the frame, a U-shaped bridge contact conforming in shape to and mounted on the free end of the lever, a U-shaped body of insulation between said contact and the free end of the lever, a pair of spaced contacts located in the path of movement of the bridging contact, a body of insulation mounted on the frame and having recesses in its sides, in which recesses the contacts are secured, the walls of the recesses being in engagement with the edges of the contacts for a portion of their length adjacent the free ends of the latter whereby the contacts are supported by said walls, an actuator pivoted on the frame, a rod which is hinged to the actuator, a coiled compression spring which surrounds the rod, the actuator, rod and spring forming a toggle, and means connecting the lever and rod and through which movements of the toggle are imparted to the lever and its bridging contact.

7. In an electric switch, the combination of a metallic frame which is U-shaped in cross-section and has integral high, low and intermediate side wall portions, a metallic lever pivotally mounted at one end on the frame adjacent the junction between the high and intermediate side wall portions thereof, means for actuating the lever, a pair of insulated contacts, a U-shaped bridging

contact mounted on the free end of the lever and arranged to bridge said pair of contacts, a U-shaped body of insulation located between the free end of the lever and its bridging contact, and a hollow insulated rivet which unites the bridging contact, body of insulation and the free end of said lever.

8. In an electric switch, the combination of a frame which is U-shaped in cross section and has high, low and intermediate side wall portions, a body of insulation seated on the bottom of the frame between the low side walls and having recesses in its sides, a fixed contact located in each of said recesses and supported for a portion of its length by the side walls thereof, a U-shaped lever pivotally supported at its open ends by the frame, said lever having an ear which extends laterally from the closed end there-

of, said ear being provided with a guide opening, a U-shaped bridging contact mounted on the closed end of the lever and arranged to bridge the fixed contacts, a rod which extends through the guide opening in the ear, a trigger which is hinged to the rod, and a spring, said rod, trigger and spring forming a toggle means for moving the lever to carry the bridging contact into and out of bridging engagement with the fixed contacts by a snap action, the movement of the lever and bridging contact being limited in one direction by the high portion of the frame and in the opposite direction by the intermediate portion thereof.

In witness whereof, I have hereunto set my hand this 1st day of March, 1924.

FRANK C. DE REAMER.
